CONCRETE-BREAKING MACHINE.

1,381,314.

Specification of Letters Patent. Patented June 14, 1921.

Application filed April 19, 1920. Serial No. 374,814.

To all whom it may concern:

Be it known that I, LEO A. KRUPP, a citizen of the United States, and a resident of Findlay, in the county of Hancock and State 5 of Ohio, have made an Invention Appertaining to Concrete-Breaking Machines; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to machines for breaking concrete or the like, and is particularly intended for use in breaking up concrete pavements preparatory to repairing, trench work, or other purposes.

20 The object of my invention is the provision of a portable machine of the class described, having a drop hammer or weight adjustable to strike a light or heavy blow and also adjustable crosswise of the machine, or 25 of the path of travel, to break a path of concrete of any width up to the limit of the machine, thereby adapting it for use in cities where nearly all paved streets have 30 nearly of breaking the concrete for repaving and trench work is difficult and expensive. The machine may also be used equally well for tamping purposes.

Further objects and advantages of the 35 invention will be apparent from the following detailed description thereof.

While the invention, in its broader aspect, is capable of embodiment in numerous forms, a preferred embodiment thereof is 40 illustrated in the accompanying drawings, in which,—

Figure 1 is a side elevation of a machine embodying the invention. Fig. 2 is a top plan view thereof with parts broken away. 45 Fig. 3 is a rear end elevation thereof with parts broken away. Fig. 4 is an enlarged section on the line 4, 4 in Fig. 3, and Fig. 5 is a section on the line 5, 5 in Fig. 3 with parts broken away. Fig. 6 is a front elevation of the parts shown in Fig. 5.

50 Referring to the drawings, 1 designates the tractor frame, supported in the rear by a pair of transversely spaced tractor wheels 2, 2 of the caterpillar type, and in front by 55 a pair of steering wheels 3, 3, in any suitable

manner. An engine 4 is carried by the frame at its forward end and has driving connections 5 with a reverse gear transmission mechanism inclosed within a case 6 and controlled from a handle 7 (Fig. 1) through 60 a shaft 8. The transmission mechanism has chain and sprocket wheel connection with a shaft 10 journaled transversely in the frame at the rear of the engine. This shaft is run at a constant speed in either direction by 65 the engine and has a two speed driving connection with a differential jack-shaft 11. The high speed connection is through a clutch controlled pinion 12 on the shaft 10 and a meshing gear 13 forming part of a 70 differential gearing on the jack-shaft 11. A clutch 14 on the shaft 10 is movable into and out of engagement with the pinion 12. The low speed drive is through a clutch controlled chain and sprocket wheel connection 15 be- 75 tween the shaft 10 and a jack-shaft 16, and the shaft 16 has a pinion 17 in mesh with the differential gear 13 and shiftable into and out of engagement therewith. The differential shaft 11 has driving chain and 80 sprocket wheel connection 18 at each end with the respective caterpillar wheel 2.

The frame 1 is provided at its rear end with a plurality of transversely spaced uprights 19 and at the rear thereof at each end 85 with an upright 20 all suitably tied together and forming a tower. This tower is braced with respect to the frame 1 and the members thereof rigidly connected by a frame-work 21 of any suitable construction.

90 A carriage or guide frame 22 in which a weight 23 is vertically movable is suspended from the top portion of the tower between the two uprights 20 thereof and is shiftable transversely of the frame 1 between said uprights. The carriage comprises four corner uprights 22^a of angle-iron arranged in rectangular form and tied together by top and bottom connecting members 24. The carriage is provided at its top with two sets of 100 double over-head track rollers 25, which travel on respective horizontal flanges of a track rail 26 connecting the uprights 20 at the top of the tower, as best shown in Figs. 3 and 4.

105 Two cross-beams 27 are provided on the carriage 22 at the inner side of its top portion in slightly vertically spaced relation, and between these at each end is mounted a roller 28 for bearing forwardly against a 110

cross guide-rail 29 on the uprights 19 of the tower. The lower end of the tower extends below the frame 1 and is provided adjacent to such end at its inner side with a pair of channel rollers 30, which rest on a track rail 31 mounted on the frame 1 crosswise thereof at the base of the tower. It is thus evident that the guide frame 22 is carried by the tower and frame 1 for free movement transversely thereof throughout the width of the frame. A squared shaft 32 extends crosswise of the upper portion of the tower at the outer side of the carriage 22, being journaled at its ends to bearing brackets 33 projecting rearward from the upper end portions of the tower uprights 20. The squared portion extends through a bushing 34, which is journaled at its ends in bearings 35 on the outer side of the upper end portion of the guide frame 22, and also has a sprocket wheel 36 fixed to each end thereof without the carriage, whereby the bushing and sprocket wheels are caused to turn with the shaft 32 and are permitted to have movements longitudinally thereof with the carriage. The carriage 22 is provided at the outer side of its lower end portion with a bearing bracket 37 in which a cross shaft 38, carrying a sprocket-wheel 39 at each end thereof without the guide frame, is journaled. A sprocket-chain 40 connects the sprocket wheels 36 and 39 at each side of the guide frame, with the inner length of each chain parallel with and adjacent to the cross vertical center line of the carriage. The chains are provided at intervals with hooks 41 arranged in horizontally aligned pairs on the two chains and associated with each hook is an angled trip lever 42 having a control arm projecting inwardly from the chain and a short arm movable across the hook 41 to eject therefrom an article which is being elevated by the hook during the upward inner course of movement of the chain.

The weight 23 is provided at its upper end with a short cross-shaft 43 to which the lower end of a rocker arm 44 is pivoted for vertical rocking movements longitudinally of the frame. This arm is provided at its upper end with a cross shaft 45, the ends of which project into position at the forward side of the upper length of each chain 40 to be engaged by the hooks 41 in their upward movement with the chain so that the arm and connected weight are elevated by the chain. The arm 44 is weighted at its rear side, as shown at 46, to normally retain the arm in upright position with its shaft 45 in the path of movement of the upwardly traveling chain hooks 41. When the weight has been elevated a predetermined extent by the chains 40 the inwardly projecting control arm of the trip levers 42 will have

moved into engagement with respective trip members 47 disposed in the path of movement thereof and will be moved to eject the shaft 45 outward from the hooks 41 with which engaged, thereby permitting a dropping of the weight 23.

The shock of engagement of the moving chain hooks 41 with the weight arm 44 is cushioned or reduced to a minimum by connecting the arm 44 to the weight through the medium of a fluid cushion connection. This is accomplished, in the present instance, by providing a dash-pot 48 in the upper end of the weight 23 in which a plunger 49 operates, the stem of the plunger being projected without the dash pot and carrying the shaft 43 of the arm 44.

The trip members 47 are carried at the ends of a cross-bar 50 which is adjustably clamped to the carriage 22 for adjustment vertically thereof. A clamping strip 51 (Fig. 1) is disposed at the inner side of the cross-bar 50 and the two are drawn together in binding relation to adjoining flanges of a pair of uprights 22a of the carriage by a hand-screw 52.

The squared shaft 32, which drives the weight elevating chains 40, 40, has a sprocket wheel 53 on one end, which is connected by a sprocket chain 54 to a drive sprocket-wheel 55 on the outer end of the shaft 10, the sprocket wheel 55 being much smaller than the sprocket wheel 53 to reduce the speed of driving of the shaft 32 relative to the shaft 10. The sprocket wheel 55 is loose on the shaft 10 and is engaged with the shaft by a shiftable clutch member 56, which is splined on the shaft and has its shifting movements controlled by any suitable means, not shown.

The sleeve 34 at the upper end of the carriage 22 has a ratchet wheel 57 fixed thereto to turn with the shaft 32 and this ratchet wheel is connected by a hook pawl 58 to prevent a back turning of the shaft 32 when the sprocket wheel 55 is disconnected from the shaft 10. This enables the weight 23 to be held in elevated position by the elevating means during the moving of the machine from one place to another.

The shifting of the carriage 22 transversely of the machine is effected by the movement of an endless chain 59, which extends crosswise of the tower and is guided at its ends around sprocket-wheels 60 carried by horizontal shafts 61, which are journaled lengthwise of the frame in bearings provided on the uprights 19 and 20 at each side of the tower. The chain 59 has one length thereof connected to the carriage 22 through the medium of a U-bolt and cross-bar 62 fixed to the inner side of the carriage frame. One of the shafts 61 has a sprocket-wheel 63 fixed to its forward end and connected by a sprocket chain 64 to a smaller sprocket wheel 65 on a shaft 66 journaled in

the rear end portion of the frame 1 longitudinally thereof. The shaft 10 carries two loose bevel gears 67 each in mesh with a bevel-gear 68 on the forward end of the shaft 66 at opposite sides of its axis. A clutch member 69 is feathered on the shaft 10 intermediate the gears 67, 68 and is shiftable into engagement with either to cause a driving of the shaft 66 in one direction or 10 the other from the shaft 10 and to impart a corresponding movement of the carriage 22 crosswise of the frame.

The operation of my machine is as follows:—

- 15 The engine being in operation the operator effects a forward or reverse running of the machine by throwing the control lever 7 into one or the other of its positions, and he also controls the speed of movement of the 20 machine by throwing the clutch 70 on the shaft 10 into engagement with the connection 15 so that the driving is through the shaft 16, pinion 17, differential gearing 13, shaft 11 and connections 18 with the caterpillar wheels. To obtain the high speed 25 running of the machine, the clutch 14 on the shaft 10 is thrown into engagement with the pinion 12 thereby effecting a driving of the differential gearing. To effect a driving of 30 the weight elevating chains 40 the clutch 56 on the shaft 10 is thrown into engagement with the sprocket wheel 55, which is connected to and drives the squared shaft 32 through the sprocket chain 54 and wheel 53. 35 The continuous and constant speed movement which is imparted to the chains 40 successively brings pairs of hooks 41 thereon into picking-up engagement with the cross-arm or shaft 45 of the weight so that the 40 weight is successively raised by each engaging pair of hooks until the trip levers 42 in association with the hooks move into tripping engagement with the trip members 47 on the cross-bar 50, fixed to the carriage 45 frame 22 and are moved thereby to eject or swing the shaft 45 out of engagement with the hooks, which permits the weight to drop and break any concrete or other breakable means within its path of movement. After 50 the cross-shaft 45 has passed from engagement with a pair of elevating hooks 21 it is caused to swing back to its normal upright position by the weighted portion 46 thereof, it being understood that the catch arm 55 44 swings on the pivot 43, which has yielding connection with the weight 23. The force of the blow to be delivered by the weight 23 is gaged by the point in its elevating movement at which it is tripped by 60 the trip members 47, said members being adjustable vertically of the carriage for such purpose. The carriage 22 may be moved in either direction transversely of the machine by throwing one or the other of the gears 67 on the shaft 10 into engagement there-

with thereby effecting a driving of the chain 59 through the shaft 66, chain 64, sprocket wheel 63 and shaft 61. This transverse adjustment of the carriage may be effected either when the machine is at rest or in movement and during a driving of the weight elevating chains 40 or when said chains are at rest. It is thus evident that I have provided a machine for breaking-up concrete pavements or the like which may be operated to break a path of any width within the limits of the machine and of any length.

I wish it understood that my invention is not limited to any specific construction, arrangement or form of the parts, as it is capable of numerous modifications and changes, without departing from the spirit of the claims.

Having thus described my invention, what I claim as new, and desire to secure by Letters Patent, is,—

1. In a machine of the class described, a portable frame having a tower at one end, a carriage carried for horizontal adjustment by the tower and forming a vertical guide, a weight guided for movement by the carriage, an elevating chain associated with the carriage for movement therewith and having a length extending longitudinally of the carriage, said chain having a hook, means movably carried by the weight and adapted to be engaged by the chain hook to cause an elevation of the weight by the chain, and means automatically operable to release the hook engaging means from the hook to permit a dropping of the weight when elevated a predetermined height.

2. In a machine of the class described, a portable frame having a tower, a carriage carried for horizontal adjustment by the tower, means operable to adjust the carriage, a weight guided for vertical movements by the carriage and having a transversely movable member at its top, means operable to intermittently engage the weight member and elevate it, and means automatically operable to release the weight member from the elevating means when at a predetermined height in its movement and to permit a dropping of the weight and member, said releasing means being adjustably carried by the carriage to vary the height at which the weight is released.

3. In a machine of the class described, a portable frame, a shaft therein, a carriage shiftable longitudinally of said shaft and forming a vertical guide, a weight movable in said carriage, a catch arm pivoted to the upper end of the weight for vertical swinging movements and normally standing in one position of its movement, an elevating chain movable with the carriage and driven by said shaft and having an upward course of movement lengthwise of the carriage,

hooks carried by said chain each for engaging said catch arm and elevating the weight during a predetermined portion of the chain movement, and means automatically operable at a predetermined point in a movement of the catch arm with the chain to disengage the connection therebetween.

4. In a machine of the class described, a portable frame, a horizontal shaft journaled therein, a carriage movable lengthwise of the shaft and forming a vertical guide, a weight movable in said guide and having catch means at its top, means operable by the shaft for periodically engaging the weight means and elevating the weight, and means automatically operable to disengage the elevating means and weight means at a predetermined point in an elevation of the weight to permit a dropping of the latter.
- 10 5. In a machine of the class described, a portable frame, a horizontal shaft mounted in said frame, means for driving said shaft, a carriage carried by the frame for shifting movements lengthwise of the shaft and forming a vertical guide, a weight movable in said guide, chains guided for movement lengthwise of the carriage and driven by the shaft and operable to intermittently en-

gage and elevate the weight from lowered position, and means automatically operable 30 to release the engagement between the chains and weight at a predetermined point in an elevation of the latter.

6. In a machine of the class described, a portable frame having vertically spaced 35 horizontal tracks, a carriage having guide means for traversing said tracks to support the carriage in the frame, a weight guided for vertical movements by said carriage, a shaft journaled in the frame longitudinally 40 of the line of movement of the carriage in the frame, elevating means movable with the carriage and operable by the shaft to intermittently engage and elevate the weight, means automatically operable to release the 45 weight from the elevating means at a predetermined point in an elevation of the weight, a source of power on the frame, and means selectively operable to connect the power to said shaft to drive it and to connect the power to the carriage to shift the same in the frame.

In testimony whereof I have hereunto signed my name to this specification.

LEO A. KRUPP.
